Square D Company, Detroit, Mich., a corpora-
tion of Michigan

Application February 3, 1943, Serial No. 474,503

4 Claims. (Cl. 175—341)

1

This invention relates to an electromagnetic operator for an electric switch and has for its object the provision of such an operator which shall include a rectilinearly movable plunger armature guided at its opposite ends so as to properly space the same from the stationary magnetic elements.

Another object of the invention is the provision of an electromagnetic operator for an electric switch in which the operator includes a plunger armature having its interior end formed in the shape of a truncated cone seating within a complementary recess in a stationary magnetic core member, the diameters of the cone and recess being such as to prevent engagement of the sides of the cone and recess when the armature plunger is seated.

Other objects and features of the invention will be readily apparent to those skilled in the art from the specification and appended drawing illustrating certain preferred embodiments in which:

Figure 1 is a side elevational view of the switch according to the present invention with a portion thereof broken away.

Figure 2 is a vertical sectional view taken on the line II—II of Figure 1.

Figure 3 is a horizontal sectional view taken on the line III—III of Figure 2.

Figure 4 is a partial sectional view similar to Figure 2 but showing the contacts in engaged position.

Figure 5 is a top plan view of the switch with portions broken away.

The electric switch, as illustrated in the drawings, comprises a base 1 composed of two plate members 2 and 3 formed of insulating material. A pair of conducting connecting members, 4 and 5, having contact faces 6 and 7 provided at the inner ends thereof are disposed at the underside of the base and have projections 8 and 9 thereon adapted to be received within openings 11 and 12 provided in the insulating plate member 3, to thereby properly locate the connecting members 4 and 5 and to prevent their turning out of position. The connecting members 4 and 5 are rigidly secured to the base 1 by a pair of terminal studs 13 and 14, passing through aligned openings in the connecting members and the insulating members 2 and 3, and their cooperating nuts 15 and 16. A washer 17 is disposed beneath each of the nuts 15 and 16. A second pair of nuts 18 and 19 are provided on the studs 13 and 14 whereby circuit wires (not shown) may be secured to the switch. A pair of washers 21 and

2

22 are provided between each pair of nuts 15 and 18, and 16 and 19.

A magnetic plate 23 is carried on top of the base 1 and is secured thereto by rivets 24, one of which is illustrated in Figure 1. The rivet 24 includes a guide portion 25 which is internally threaded and serves a purpose to be hereinafter described. A second magnetic plate 26 is disposed within an opening 27 provided in insulating member 2 and is so positioned relative to plate 23 that an opening therein is placed in alignment with an opening provided through plate 23. A magnetic sleeve or core member 28 having shoulder portions 29 is supported thereby on plate 23, and has a shank portion 31 which extends through the aligned openings of plates 23 and 26. The rim of the shank portion 31 is bent outwardly to hold plate 26 in intimate contact with plate 23 and to rigidly secure the sleeve member 28 in position. An energizing coil 32 comprising a spool sleeve 33 of fiber composition and spool washers 34, also of fiber composition, is disposed about the sleeve 28 with the latter member being contained except for the shank portion 31, wholly within the opening in coil 32 provided by sleeve 33. A shell or cover 36 is fitted over the coil 32. The cover 36 is provided with mounting flanges 37 which rest upon the magnetic plate 23. Studs 38 passing through base 1 and the magnetic plate 23 are threaded into the flanges 37 to thereby secure shell 36 to the base. A felt washer 39 is provided on top of the coil 32 and spaces the cover 36 from the coil. A stationary core member 41 having a recess 42 extending from the top surface thereof is carried by the cover 36, being secured thereto in a manner similar to that in which sleeve member 28 is secured to plate 23, there being shoulder portions 43 provided on the member 41 which bear against a magnetic plate 44 and a shank portion 45 which extends through an opening in the cover, and the rim of the shank portion is bent outwardly to rigidly fix the core member 41 in place. The core member 41 is provided with a recess 46 extending from its bottom surface and being of a truncated cone shape. The recess 42 extending from the top surface of member 41 and the recess 46 extending from the bottom surface thereof are joined by a passageway 47 for a purpose to be hereinafter described. Mounting of the shell 36 in position on the base 1 will place the greater portion of the core member 41 within the opening in coil 32, but the length of the core member 41 is such that the lower extremity thereof will be spaced a sufficient distance

from core member 28 that flux leakage therebetween is held to a minimum.

Within recess 42 a spring seat 48 and a spring 49 are disposed. A sealing plate 51 is riveted to the cover 36 and closes the recess 42 and prevents access to within the cover 36. A boss 52 is formed in the sealing plate 51 and serves as a spring seat for positioning the upper end of spring 49. A second pair of terminal studs 54 and 55 are carried by the base 1, being held thereon by nuts 56. To each of the studs 54 and 55, a wire 57, leading from the solenoid coil 32, is secured by a stud 58, as is also an external circuit wire (not shown) whereby electrical energy may be brought to the energizing coil 32. A plunger or armature 53 is disposed within the sleeve member 28 and passes through an opening in insulating member 2 and normally rests upon the surface of insulating member 3. A portion 59 of lesser diameter than the main body of the armature 53 extends from the bottom portion thereof and through an opening 61 in the insulating member 3 and is closely received thereby. A guide pin 62 formed of non-magnetic material is staked or otherwise secured to the top surface of the armature 53 and extends through passageway 47 in core member 41 into recess 42. Spring seat 48 fits over the end of pin 62 whereby upward movement of the armature 53 will be against the bias of spring 49. An extension 63 is provided at the end of portion 59 of the armature 53 and supports a movable contact assembly or switching member 64. The movable contact assembly 64 comprises a member 65 formed of insulating material and a conducting member 66 riveted thereto, with the conducting member 66 having an opening 67 through the center thereof and carrying contact surfaces 68 and 69 at opposite ends thereof adapted to bridge and cooperate with the stationary contact faces 6 and 7 to make and break an electrical circuit therethrough. Raised portions 71 provided on the insulating member 65 space this member from the connector 66. Extension 63 of the armature 53 passes through an opening in member 65 and through opening 67 in connector 66. To mount the movable contact assembly 64 thereon, a spring member 73 with its spring seats 74 is provided upon the extension 63 and held thereon by a cotter pin 75. The spring member 73 will normally exert its bias upon the insulating member 65 to hold it in its uppermost position and against shoulder portions 76 provided on portion 59 of armature 53 as shown in Figure 2. The insulating member 65 is slotted at either end as at 77 and 78, and these slotted ends are disposed about guide portions 25 and cooperate therewith to properly position the movable contact assembly 64 and to fix the path of movement thereof so that the contact assembly will move in a substantially rectilinear path on movement of the armature or actuating member 53 upon energization and deenergization of the coil 32. A cover 79 formed of molded Bakelite is disposed over the movable contact assembly 64 to seal off the switch from outside access. Studs 81 threaded into guide portions 25 secure the cover to the base 1.

A mounting bracket 82 is carried by the solenoid cover 36 whereby the switch may be located in the desired location.

It is to be noted that the armature 53 is guided in its movements by the guide pin 62 and the armature portion 59. The pin 62 and the armature portion 59 are closely received by the

spaced concentric openings 47 and 61 provided by core member 41 and the insulating member 3 and lateral movement of the armature 53 and side pull thereon is thereby held to a minimum and there is no contact between the sides of the armature 53 and the interior surface of sleeve member 28 on movement of the armature 53 thereby avoiding friction loss.

With the construction here described, a more effective device is secured, for there is no necessity for the insertion of a brass sleeve or other liner between the interior surface of the sleeve member 28 and the armature 53 and thus the air gap will comprise only the mechanical clearance between the armature 53 and the sleeve member 28, and, therefore, the magneto-motive force required to move the armature is materially lessened over that which would be required if the air gap were to include the thickness of a brass liner.

The lateral sides 83 defining the recess 46 in the stationary core member 41 are of the same angle as the lateral sides 84 of armature 53 but the diameter of the surface 85 defining the recess is slightly greater than the diameter of the upper end 86 of the armature 53 so that there is no interference mechanically between the lateral surfaces 83 of the armature 53 and the lateral surfaces 84 defining the recess 46, and the armature 53 will complete its full stroke into engagement with surface 85 without frictional loss due to contact with the sides 83. A comparatively steep cone angle is thus utilized to provide for a relatively high initial pull on the plunger 53 without the danger of the plunger sticking tight before a full stroke has been completed.

In the operation of the device of the present invention, assuming the parts to be in the position of Figure 2, energization of coil 32 will effect an upward rectilinear movement of armature 53 against the bias of spring 49 and into sealing engagement with surface 85. Movement of the armature 53 carries extension 63 upwardly to apply force upon spring 73; this force is transmitted by the spring to the insulating member 65 to move it also upwardly to thereby carry the movable contacts 68 and 69 into bridging engagement with the stationary contacts 6 and 7 to complete a circuit therethrough. It is to be noted in Figure 4 that when the contacts are in engaged position there is a definite compression of the spring 49 which results in an application of force on the movable contacts 68 and 69 to effect a substantial contact pressure between these contacts and the stationary contacts 6 and 7.

On deenergization of the coil 32, the plunger 53 will move downwardly under the force of gravity and the bias of spring 49 to move the movable contact assembly 64 and break the circuit. The device need not be mounted in vertical position as shown, for the spring 49 is made sufficiently stiff that it applies a force that will always return the plunger 53 to its deenergized position to break the circuit through the switching assembly regardless of the position in which the device is mounted.

While certain preferred embodiments of the invention have been specifically disclosed, it is understood that the invention is not limited thereto, as many variations will be readily apparent to those skilled in the art and the invention is to be given its broadest possible in-

terpretation within the terms of the following claims.

What is claimed is:

1. An electromagnetic operator for an electric switch, comprising an insulating base, a movable armature member, an energizing coil for effecting movement thereof and having an opening therethrough, a pair of core members disposed within said opening in said energizing coil, said core members being spaced from one another and each of said core members having openings therein, said armature member being movable for the greater part of its length within one of said core members, a non-magnetic member carried by said armature member and received by the opening in the second of said core members, and an extension on said armature member adapted to pass through an opening in said insulating base, said opening in said second core member and said opening in said insulating base being concentric whereby said armature member will be held continually spaced from the sides of the core members through which it moves for a greater part of its length to effect an air gap between the armature and the sides of said latter core member comprising only the mechanical clearance therebetween.

2. An electromagnetic operator for an electric switch, comprising an armature member, an operating coil for effecting movement thereof and having an opening therethrough, a pair of magnetic members spaced from one another and disposed at either end of said opening in said operating coil, the first of said magnetic members having an opening therethrough and receiving said armature member for movement therein on energization of said operating coil, means carried by said armature member for holding it spaced from the sides of said first magnetic member when moving therein to effect an air gap between said armature and first magnetic member, said armature member having an end portion thereof formed in the shape of a truncated cone, said second magnetic member having a recess therein formed in the shape of a truncated cone and of a sufficiently large diameter than the diameter of the end portion of the armature that when said end portion of said armature member is received, upon energization of said coil, engagement with the sides of the recess is avoided.

3. An electromagnetic operator for an electric switch, comprising an insulating base, a movable armature, an energizing coil for effecting movement thereof from a first position, said energizing coil having an opening therethrough, a pair of magnetic members disposed within said opening and spaced one from the other, the first of said magnetic members having an opening therethrough and receiving said armature for movement therein on energization of said energizing coil, means for centering said armature to prevent engagement with the sides of said first magnetic member, and to effect an air gap therebetween comprised only of the mechanical clearance between said armature and the sides of said first magnetic member, said means comprising a non-magnetic member secured at one end of said armature member and being closely re-

ceivable within an opening in the second of said magnetic members and an extension on said armature member which is closely receivable within an opening in said insulating base, said second magnetic member having a recess therein into which said non-magnetic member extends and is movable therein, spring means disposed in said recess and acting on said non-magnetic member to return said armature to said first position upon deenergization of said coil.

4. An electromagnetic operator for an electric switch, comprising an armature member, an operating coil for effecting movement thereof, a pair of magnetic members spaced one from the other and disposed at either end of an opening in said operating coil, the first of said magnetic members having an opening therethrough and receiving said armature member for movement therein for the greater portion of its length on energization of said operating coil, said armature member having an end portion thereof formed in the shape of a truncated cone, said second magnetic member having a recess therein formed in the shape of a truncated cone and of sufficiently larger diameter than the diameter of the end portion of the armature member that when said end portion of said armature is received, engagement with the sides of the recess is avoided, means carried by said armature member for holding it spaced from the sides of said first magnetic member when moving therein to form an air gap between the armature and first magnetic member, said means comprising a non-magnetic member provided at one end of said armature member and an extended portion at the opposite end of said armature member, said non-magnetic member extending into said recess in second magnetic member and through a connecting passageway and into a second recess provided therein, and spring means disposed in said second recess and acting on said non-magnetic member to return said armature to deenergize position on deenergization of the coil.
